Primary Examiner — Ieisha N Price

(57) **CLAIM**

The ornamental design for a bed connector as shown and described.

DESCRIPTION

FIG. 1 is a front, right and bottom perspective view of a bed connector showing my new design;
 FIG. 2 is a rear, left and top perspective view thereof;
 FIG. 3 is a front elevational view thereof;
 FIG. 4 is a rear elevational view thereof;
 FIG. 5 is a left view thereof;
 FIG. 6 is a right view thereof;
 FIG. 7 is a top view thereof;
 FIG. 8 is a bottom view thereof; and,
 FIG. 9 is an environment perspective view of the bed connectors, shown in a state of use; and,
 FIG. 10 is an exploded perspective view of FIG. 9.
 The broken lines in FIGS. 9 and 10 illustrating a bed connector, depict environmental subject matter that forms no part of the claimed design. The broken lines in FIG. 7 illustrate portions of the bed connector that form no part of the claimed design.

1 Claim, 10 Drawing Sheets(56)
